UNITED STATES PATENT OFFICE.

WILLIAM M. MATTEOLI, OF CONNERSVILLE, INDIANA, ASSIGNOR TO INDIANA LAMP COMPANY, OF CONNERSVILLE, INDIANA, A CORPORATION.

ТИЛТИНГ РЕФЛЕКТОР МОНТИНГ ФОР ЛАМПС.

Application filed February 26, 1923. Serial No. 621,298.

To all whom it may concern:

Be it known that I, WILLIAM M. MATTEOLI, a citizen of the United States, and a resident of Connersville, county of Fayette, 5 and State of Indiana, have invented a certain new and useful Tilting Reflector Mounting for Lamps; and I do hereby declare that the following is a full, clear, and exact description thereof, reference being 10 had to the accompanying drawings, in which like numerals refer to like parts.

This invention relates to a tilting reflector construction embodied in a head-lamp, and more particularly to the means 15 for pivotally mounting the reflector within the lamp casing, and the protection of the reflector so mounted from dust and moisture.

The main feature of the invention resides 20 in the spring for pivotally securing the reflector within the lamp casing in such a fashion as to yieldingly and normally maintain it in tilted position. Such pivotal mounting permits the reflector to be actuated to other positions about an axis through 25 its pivot points, but upon release of the actuating means will cause it to return to its normal position under spring tension. Whereas heretofore tilting reflectors have 30 been pivotally mounted within the casing by pivot pins, hinges or spring mountings allowing it to freely pivot, in all such cases it has been necessary to provide a spring other than the pivotal means for returning 35 the reflector to normal position after having been actuated. This structure avoids the necessity of using a separate return spring and in addition, so supports the reflector as to prevent its becoming loose, and 40 rattling from wear.

The full nature of this invention will be understood from the accompanying drawings and the following description and claims.

45 In the drawings Fig. 1 is a horizontal section through a lamp showing the pivotal mounting of the reflector therein. Fig. 2 is a section taken on the line 2-2 of Fig. 1. Fig. 3 is a section taken on the line 3-3 50 of Fig. 1 showing the reflector in one extreme position by means of the full lines and in the other extreme position by means of dotted lines.

In the drawings there is shown a lamp 55 having a casing 10, a lens rim 11 and lens

12. Pivotally mounted within the casing there is a reflector 13 provided with a lamp socket 14 in the rear thereof. The casing 10 is provided with an annular bead 15 formed about the open end thereof, said bead continuing in an inwardly extending annular flange 16 and from thence doubling on itself to form an outwardly extending annular resilient flange 17 with a forwardly extending flange 18.

60 Mounted within the forward end of the casing there is a reflector supporting ring 19 having a rear outwardly extending flange 20 and a forward inwardly extending flange 21. The casing flange 17 and the ring flange 70 20 are provided with annular recesses adapted to abut each other between which may be clamped a cord or similar sealing means 22 for preventing dust or moisture from entering the casing between the casing 10 75 and enclosure rim 11. The outer inwardly extending flange 21 is provided with an annular recess for receiving the cord or sealing means 23 for preventing dust or moisture from entering between the lens 12 80 and closure rim 11. The lens 12 may be mounted in the closure rim by means of a plurality of inwardly extending fingers or hooks 24 rigidly secured to the inner periphery thereof. When the rim is secured 85 upon the casing by any suitable means, not shown herein, it forcibly clamps the lens 12 against the ring 19 through the cord 23 and further clamps the ring 19 against the flange 17 of the casing through the sealing cord 22.

90 For pivotally mounting the reflector 13 within the casing there is provided a pair of spiral springs 25 mounted one on each side of the reflector in a horizontally and 95 diametrically opposed position. One end of each of said springs is extended so as to be secured to the flange 26 of the reflector by the bolt 27 and the other end of each of said springs is rigidly secured to the flange 20 of the ring 19 by the bolts 28. The coil springs 25 are disposed laterally in alignment with the horizontal diameter or 100 pivotal axis of the reflector so that they normally force the reflector into forward 105 and downwardly tilted position, as shown in full lines in Fig. 3.

110 For actuating the reflector there may be provided a rod 29 pivotally secured at its upper end between the ears 30 of the lamp

socket 14 and thence extending downwardly through the bottom of the casing 10 in position to be connected in any suitable manner to the operating means employed for 5 tilting the reflector. As the springs 25 maintain the reflector in its downward position, when the rod 29 is pulled downwardly it causes the reflector to be tilted about said springs to an upward position, as shown by 10 dotted lines in Fig. 3. Upon the release of the rod 29 the tension of the springs 25 exerted upon the reflector will immediately cause it to return to its downward position without further action of the rod 29 or 15 any additional spring or any auxiliary spring structure. It will be observed that the reflector, being pivotally supported in this manner cannot become loose or caused to rattle by vibration or through wear, since 20 there are no relatively movable parts embodied in the pivoted supports, but the reflector will at all times be fixedly held in position by means of the bolts 27 and 28. While as above described, the springs shown 25 herein are so arranged as to normally maintain the reflector in its downward position, they may be so arranged, if desired, as to normally maintain it in vertical or upward position.

30 The invention claimed is:

1. A lamp structure comprising a lamp casing, an enclosure for said casing, a reflector movably mounted in said casing, means for actuating said reflector, and a 35 pair of springs for pivotally supporting said reflector within said casing, said springs being secured at one end to said reflector and at the other end to a part of said casing in such manner as to permit pivotal movement of said reflector with respect to said casing through said springs and maintain said reflector in normal position by means of the spring tension exerted between the 40 fixed ends thereof.

45 2. A lamp structure comprising a lamp

casing, a closure for said casing, a reflector movably mounted in said casing, means for actuating said reflector, and a pair of springs mounted on opposite sides of said reflector in a horizontal and axial plane 50 therethrough, said springs being so secured between said reflector and casing as to pivotally support the former in the latter and to resiliently permit its vertical tilting 55 movement about a horizontal axis and return said reflector to normal position by the spring tension thereof after being actuated.

3. A lamp structure comprising a lamp casing, a closure for said casing, a reflector 60 provided with an annular outwardly extending flange, said reflector being removably mounted in said casing, a supporting ring supported by said casing, means for actuating said reflector, and a pair of diametrically opposed spring supports, the inner 65 ends thereof being rigidly secured to the flange of said reflector and the outer ends rigidly secured to said ring, whereby said reflector will be pivotally supported within 70 said casing by said springs and be returned to normal position by the spring tension thereof after having been actuated.

4. A lamp structure comprising a lamp casing, a closure for said casing, a reflector 75 movably mounted in said casing provided with an annular outwardly extending flange, means for actuating said reflector, a supporting ring carried by said casing, sealing means mounted between said closure and 80 ring, a second sealing means mounted between said ring and casing for preventing dust and moisture from entering therein, and a pair of springs for pivotally supporting said reflector on said ring and returning it to normal position by the spring tension 85 thereof after being actuated.

In witness whereof, I have hereunto affixed my signature.

WILLIAM M. MATTEOLI.
